JEAN GURNE, OF ROUEN, FRANCE

GAUGE-RECORDING DEVICE FOR WIRE-DRAWING MACHINES

Application filed March 12, 1931, Serial No. 522,463, and in France March 20, 1930.

The present invention relates to a gauge-recording device for wire-drawing machines and has for its primary object to provide a device which will accurately record or register minute inequalities in the diameter, gauge, roundness or hardness of the wire.

A further object of the invention is to provide a device of this character capable of recording or indicating in a highly legible way minute inequalities in the diameter, gauge, roundness or hardness of the wire, the indication furnished by this device being in the form of a line traced on a sheet of paper or similar recording material and giving a vivid illustration of the inequalities in question which makes it possible to readily locate those lengths or portions of the drawn wire presenting said inequalities. The ability to locate these unequal portions of the wire and throw them away at will is valuable for many purposes such for example as the making of card clothing wires.

A still further object of the invention is to provide a device of the aforesaid character associated with the die of a wire-drawing machine for recording in a magnified way minute inequalities in the diameter, gauge, roundness or hardness of the wire, said inequalities being of the order of one hundredth of a millimeter, thus making it possible to discard those portions of the wire which suffer from said inequalities to put on the market a perfectly gauged wire.

Still a further object of the invention is to provide a device of the character set forth of simple and rugged construction involving springs adapted to elastically sustain the tractional stresses undergone by the die through which the wire is drawn, thereby avoiding any jerks due to the varying resistance offered by said wire.

With these and such other objects in view as will incidentally appear hereafter, the invention comprises the novel combination and arrangement of parts that will now be de-

scribed in detail, reference being had to the accompanying diagrammatic drawing which shows non-limitatively one of the various mechanical forms in which the principle of the invention may be employed. 50

In the drawing:

Figure 1 is a fragmentary top plan view showing the wire-drawing machine comprising the elastically held die through which the wire is drawn and the gauge-recording device associated with said die. 55

Figure 2 shows on an enlarged scale the record line illustrating the evenness of a wire drawn in a machine like the one shown in Fig. 1. 60

Figures 3, 4 and 5 are representations similar to Fig. 2 but assuming the wire that has been drawn to show certain inequalities that are registered and magnified in a highly legible and striking way by each record line. 65

Reference being first had to Fig. 1, *a* designates the wire, *b* the drum on which said wire is wound after being drawn, *c* an arrow showing the direction in which the wire travels under traction from a conventional feeding source (not shown) towards said drum, *d* the die through which the wire is drawn, the gauge of the die opening being reckoned according to practical requirements. 70

The die *d* is elastically connected to the stationary bracket *e* through a pair of coil springs *f*, *f'* of suitable length and resiliency and high responsiveness or sensitiveness to inequalities of traction for allowing proper longitudinal displacements of the die *d* as will be stated hereafter. The springs, *f*, *f'* are secured at *i*, *i* on the bracket *e* and at *j*, *j* on the die holder *l*. Intermediate said springs may be located in the usual way a cup (not shown) containing lubricant through which the wire *a* passes. 75

Opposite the die holder *l* but laterally thereof is positioned a drum *m* to which is imparted in any convenient way a uniform rotational motion. For example, this drum 80

m may be supported by an arbor *s* to which is keyed a gear *t* meshing with a gear *u* keyed to an arbor *v* driven by an actuating mechanism *W* of any approved nature, such as for example a clockwork mechanism or an electric motor, the actuation of which may be synchronized with the actuation of the wire drawing machine itself, and will cause stoppage of the drum *m* when said machine is stopped. The drum *m* is fitted with a sheet of paper or equivalent writing or recording surface. A stylus *o* secured to the die holder *l* is so associated with the recording drum *m* as to have its end or nib constantly contacting therewith during the wire drawing operation.

The operation of the gauge-recording device is as follows: Assuming the wire *a* that is being drawn to have such a texture or cross sectional outline throughout its length as to always offer the same resistance to the die *d*, the tensile elongation of the coil springs *f*, *f'* holding the die holder *l* with respect to the supporting bracket *e* will be constant, whereas by the stylus *o* rigidly connected to said die holder will trace on the paper or other covering of the rotary recording drum *m* a rectilinear line *p* such as the one shown in Fig. 2.

Should now a single inequality in the hardness, roundness, gauge or other characteristic of the wire *a* that is being drawn meet the die, *d*, the tensile elongation of the coil springs *f*, *f'* will at once vary, the length of said springs decreasing or increasing depending on the inequality in question involving less or more resistance to the drawing operation. The stylus *o* will therefore write, i. e. register said inequality of resistance in an illustrative way on the covering of the recording drum *m* as shown for example at *q* in Fig. 3. The shape of the tooth, notch or nick *q* thus produced on the straight record line *p* will give a true illustration of the extent of the inequality of the wire by which it will be possible to readily locate and discard the faulty or defective portion of the wire *a*, for example by immediately stopping the machine and eliminating said portion.

Similarly, a series or sequence of inequalities in the wire *a* that is being drawn will produce an irregular line showing a succession of peaks such as the ones shown at *r* in Figures 4 and 5.

It will thus be seen that the invention provides a highly sensitive gauge-recording device for wire-drawing machines which by a proper selection of the tensional characteristics of the springs *f*, *f'* will give a true and very legible illustration of any minute inequality in hardness, roundness or cross sectional area liable to occur in a wire in the course of drawing even in the case of extremely thin wires or filaments such as calibrated wires, wires used for the making of card

clothing or wires necessitating a subsequent annealing.

As above stated, the responsiveness and accuracy of the device permits the disclosure of inequalities in the diameter of the wire down to one hundredth of a millimeter. This result has never been attained by previously proposed devices which were much more complicated. The attainment of this novel result in the present device must be ascribed to the particular arrangement and co-operation of the elements which permit the springs to work as a highly sensitive dynamometer.

What I claim is:

1. In combination with a wire-drawing machine having a movable die holder and a die carried thereby, a device for automatically recording any minute inequality in the gauge, diameter, roundness or hardness of the wire submitted to the drawing operation and comprising stretchable spring means connecting the die holder to a stationary part of the machine, said spring means being so arranged as to undergo elongation by the drawing of the wire and being highly responsive and sensitive to the varying resistance offered by the die to the passing of the wire therethrough, a recording element directly associated with the die holder, and a member having a recording surface associated with the recording element, said member being movable uniformly throughout the drawing operation, and means for effecting such movement.

2. In combination with a wire-drawing machine having a die holder movable in a direction in which the wire is fed and in the reverse direction and a die carried by said die holder, a device for automatically recording any minute inequality in the gauge, diameter, roundness or hardness of the wire submitted to the drawing operation and comprising stretchable coil springs connecting the die holder to a stationary part of the machine, said springs being so arranged as to be submitted to elongation by the drawing of the wire and being of a character highly responsive and sensitive to the varying resistance offered by the die to the passing of the wire therethrough, a recording stylus rigidly fastened to the die holder, and a rotatable member having a recording surface associated with the stylus, said member being rotatable uniformly throughout the drawing operation, and means for rotating said member.

3. In combination with a wire-drawing machine having a die holder movable in a direction in which the wire is fed and in the reverse direction and a die carried by said die holder, a device for automatically recording any minute inequality in the gauge, diameter, roundness or hardness of the wire submitted to the drawing operation and comprising stretchable coil springs connecting the die holder to a stationary part of the machine,

said springs being so arranged as to be submitted to elongation by the drawing of the wire and being of a character highly responsive and sensitive to the varying resistance offered by the die to the passing of the wire therethrough, a recording stylus rigidly fastened to the die holder and projecting laterally thereof, and a rotatable drum covered with a recording surface associated with the stylus, said drum being rotatable uniformly throughout the drawing operation, and means for rotating said drum.

In testimony whereof I affix my signature.
JEAN GURNE.
